SEAMLESS STOCKING AND PROCESS OF KNITTING THE SAME.

1,110,443.

Specification of Letters Patent. Patented Sept. 15, 1914.

Application filed September 23, 1909. Serial No. 519,202.

To all whom it may concern:

Be it known that we, EDWARD E. KILBOURN, WILLIAM E. SMITH and ISAAC W. KILBOURN, citizens of the United States, 5 residing at New Brunswick, in the county of Middlesex and State of New Jersey, have invented certain new and useful Improvements in Seamless Stockings and Processes of Knitting the same; and we do hereby declare the following to be a full, clear, and exact description of the invention, such as will enable others skilled in the art to which it appertains to make and use the same.

This invention consists in the novel features hereinafter described reference being had to the accompanying drawing which illustrates our improved stocking produced by our improved process, and the said invention is fully disclosed in the following 20 description and claims.

The accompanying drawing represents a side elevation of a stocking embodying our invention.

Our improved invention is based on a new 25 discovery made by us that in order to fit the human foot a seamless stocking should be larger, that is to say, longer and wider along the foot than it is through the corresponding portion of the top of the foot, 30 or to express the same idea in another way, so that the bottom portion shall be approximately a size larger than the corresponding upper portion of the foot of the stocking, and the invention consists, therefore, in a 35 new circular knit stocking and process of knitting the same, the new stocking being knit with a sole portion between the heel and toe pockets formed of stitches of sufficiently greater length than the correspond- 40 ing courses of the top of the foot thereof to make the bottom portion of the foot longer and wider than the top portion of the foot, thus affording ample room for the bottom of the foot, and drawing the top portion, 45 which is exposed when worn with low shoes, pumps, or other slippers, snugly and neatly over the foot without wrinkling or sagging and avoiding strain along the bottom of the foot, which if present, would tend to cramp 50 the toes, draw the toe joining on the top of the foot too far forward, and drag down the reinforced portion above the heel, known in the art as the high spliced portion, and in other words, efficiently shapes and

fashions the stocking to the form of the 55 average human foot, whereby this novel structure is permanently imparted to the stocking in the process of knitting and cannot be lost in subsequent laundering.

The invention is designed especially for, 60 although not limited in its application to, a fine grade of hose in which the fabric of the leg and the top of the foot is preferably knit with a very fine yarn, and in which the portions which are subjected to the 65 greatest wear or strain are so reinforced that this thin and delicate appearing stocking will wear as well, as one knitted throughout with much heavier stock. In this class of hosiery as it has been produced heretofore, 70 the insertion of a splicing thread throughout the sole of the stocking results in making the fabric of the sole of the foot shorter, tighter, thicker, and less elastic than the corresponding number of courses on the top 75 of the foot which are knit with the regular or finer yarn only. As a result of this structural characteristic there is a greater strain lengthwise from the toe to the rib top along the sole around the heel and up the back of 80 the leg, than from the toe, over the instep and the front of the ankle and leg, when the stocking is worn. This produces a slackness over the ankle which causes the stocking to wrinkle and set badly at that point where 85 it is most exposed to view when worn with a low shoe, and is objectionable. If as is usually the case the stockings are spliced or reinforced at the back above the heel portion, this part is also shortened as com- 90 pared with the same number of courses on the front of the ankle, and accentuates the result just described. The strain of the fabric around the heel also tends to drag the reinforced portion above the heel down- 95 ward at the rear as indicated by the dotted line *z* in Figure 1 of the drawing and it is necessary to carry the reinforcing a number of courses higher on the leg as indicated by the dotted line *y*, in order to insure that 100 the stocking will be properly protected from the wear of the shoe at the rear above the heel. This carries the side portions of the spliced or reinforced portions higher than is necessary or desirable as indicated at *z*, and 105 causes the splicing to show unnecessarily when the stocking is worn with low shoes. Again, the strain around the bottom of the

foot and back of the leg before alluded to has a tendency to draw the looped union *s* where the upper edge of the toe pocket is united to the outer edge of the upper part *b* of the foot portion, too far forward upon the top of the toes where it will be exposed to undue wear.

In carrying out the improved process herein described, which may be done by hand or by a suitable knitting machine, the leg of the stocking indicated at *a* is knit in the usual manner with the desired thread or yarn. If a spliced portion is desired above the heel, the splicing thread, which is preferably though not necessarily, heavier than the splicing thread usually employed, is fed to the needles knitting the rear portion only, (or in other words the rear half or series of needles) and at the same time the stitch made by the needles taking the splicing thread is lengthened, without lengthening the stitch of the needles which are knitting the front portion of the stocking with the regular thread, thus forming the reinforced rear section *b* which is termed the "high spliced portion" for convenience of reference. The stitches forming this high spliced portion are lengthened to such an extent that the spliced portion is of greater length than the corresponding number of courses of the front portion of the stocking. The heel portion *c* may be knit in the usual manner, but it is preferred to knit it of a different yarn from that which composes the leg and foot portions, to use a heavier yarn than the splicing thread and to lengthen the stitch in knitting the heel although this is not essential. After the heel pocket is formed the foot is knit, the top portion *d* being knit with the regular or light thread, and the sole portion *e* being knit with the regular and splicing thread, and the stitch of the needles forming the sole portion is lengthened so that the sole portion *e* will be of greater length than the corresponding number of courses of the top portion of the foot. The toe pocket *f* is then formed preferably of the same thread and in the same manner as the heel and the upper edge of the toe pocket is united to the upper part of the foot portion by looping as usual. In knitting the heel and toe pockets, it is preferred to lengthen the stitch to a greater extent than when knitting the sole and "high spliced" portions and the heel and toe pockets are preferably knit with the heaviest thread employed in the stocking to provide greatest wearing qualities at those portions of the stocking.

If desired a rib top indicated at *g* can be run on the needles in a well known manner before the leg is knit, and we prefer to run in a splicing thread for a few courses at the commencement of the leg below the rib top as indicated at *a'*, the splicing extending

entirely around the leg. It is also preferred to run the splicing thread over the top of the foot during the last courses before the toe pocket is formed, as indicated at *d'*. Where the splicing thread is knit all the way around the tubular fabric as at *a'* and *d'* it is not essential that the stitch should be lengthened.

In a stocking knit by this improved process it will be seen that as the bottom of the foot is of greater length than the top, the greater strain will be from the toe over the top of the foot, and up the front of the leg, thus preventing the formation of wrinkles and causing the fabric to fit smoothly and neatly over the ankle and instep thereby shaping the stocking to conform to the shape of the human foot. In lengthening the stitches in the sole, sufficiently to make the sole portion actually longer than the corresponding portion of the top of the foot as hereinbefore described, the stitches of the sole portion are obviously coarser than those of the top of the foot, and the fabric of the sole is necessarily increased in width also, as a result of the lengthened stitches employed therein. There is no tendency to distort the high spliced portion above the heel and only the minimum number of courses need be provided to insure the protection of the stocking at that point. The spliced or reinforced portions can be made thicker than when the stocking is knit in the old way, as the lengthening of the stitches as described permits the use of a heavier reinforcing thread than could be drawn in through smaller stitches. If a splicing thread of ordinary weight is employed, the lengthening of stitches facilitates the drawing in of the splicing thread in any case and a smoother and more uniform fabric results.

While this improved process may be performed by hand it can also be conveniently carried out by means of a circular knitting machine of the type shown, for example, in Letters Patent No. 408,180 granted to E. E. Kilbourn dated July 30, 1889 by providing the top cam cylinder which operates only the series of needles knitting the back half or portion of the stocking with means whereby the downward pull of the needle in drawing the stitch can be adjusted to change the length of the stitch of said needles without affecting the character of stitch made by the other needles which are actuated by a separate cam cylinder. This can be conveniently effected by mounting the knitting cam on a vertically movable slide, and providing said slide with a set screw, operable by hand for securing the cam in different vertical positions to which it may be adjusted, or the vertical adjustment of the knitting cam can be effected automatically as desired.

The invention is also applicable to the

5 production of stockings of the well known split foot type, that is in which the top and bottom portions of the foot are formed of separate threads, the sole portion of the foot being knit with a heavier thread than that used in forming the top of the foot, or being provided with a reinforcing thread through the sole of the foot, the stitches of the sole portion of the stocking being of 10 sufficiently greater length than those forming corresponding courses of the top of the foot to secure the results of the invention.

15 It is to be noted that the lengthening of the stitches referred to herein is not merely for the purpose of enabling a heavier thread or a reinforcing or splicing thread to be more freely drawn in. The lengthening of the stitches as described performs a function beyond and more important than this in 20 that it enables the stocking to be fashioned or positively shaped in the operation of knitting to fit the foot of the wearer and at the same time adjusts and distributes the natural strains in wear so as to prevent the 25 distortion of the heel and toe pockets, and to insure a smooth and perfect fit over the instep and ankle portion of the foot.

30 In stockings knit on circular knitting machines, as heretofore made, the fabric being tubular, it tends to remain in the form of a straight tube except as the extra fullness of the heel pocket resists this tendency. Such stockings are given their final shape by means of "boards" or forms on which they 35 are stretched and pressed, but obviously this forming is lost in the subsequent laundering of the stocking. According to our invention the lengthening of the stitches through the sole, or through the sole, and heel 40 and toe, and in some cases also in the portion above the heel, produces a stocking which is actually much longer on the bottom of the foot than it is on top, irrespective of whether it is reinforced or not, and the resulting 45 stocking is thus positively given a shape conforming to that of the foot and leg of the wearer. This shaping is in the structure of the stocking and is not affected by subsequent laundering. The lengthened stitches 50 are, as a matter of fact, either composed of heavier thread or filled with a splicing thread, and the fabric comprising the lengthened stitches is not left open or slazy, as would be the case if the same knitting 55 thread were used that is used in the portions knit with the tighter stitches. This shaping or fashioning of the circular knit stocking in the manner herein described obviates the 60 objectionable features hereinbefore referred to and secures the new and desirable results before set forth.

65 Another result secured by our invention is that the elongation of the sole portion of the foot beyond the length of the top portion eliminates a plurality of courses form-

erly required to produce a stocking of any standard size, and effects a saving of yarn which would otherwise be required for the eliminated courses, the portions of which eliminated courses lying on top of the foot, 70 would if present, produce the objectionable fullness and wrinkles before referred to.

What we claim is:

1. The herein described process of knitting a seamless stocking having narrowed and widened heel and toe pockets, which consists in knitting the leg of the stocking by circular knitting with a tight stitch, then knitting the heel pocket by reciprocating knitting, and narrowing and widening, then knitting the top portion of the foot with a tight stitch, and knitting the sole portion of the foot with sufficiently longer stitches, to make it of greater length than the corresponding portion of the top of the foot, and 85 then knitting the toe pocket by reciprocating knitting and narrowing and widening, whereby the strain in use will be greater over the top of the foot and front of the ankle than around the heel and toe and along 90 the sole, thereby shaping the stocking to conform to the foot and preventing distortion of the heel and toe pockets and the formation of wrinkles in the instep and ankle 95 portions.

2. The herein described process of knitting a seamless stocking having narrowed and widened heel and toe pockets, which consists in knitting the leg of the stocking by circular knitting with a fine thread and a tight stitch, then knitting the heel pocket by reciprocating knitting and narrowing and widening, then knitting the upper part of the foot with a fine thread and a tight stitch and knitting the sole portion as a heavier 105 fabric and with sufficiently longer stitches to make the sole portion of greater length than the corresponding portion of the top of the foot, and then knitting the toe pocket by reciprocating knitting and narrowing 110 and widening, whereby the strain on the fabric in use is greater over the top of the foot and front of ankle than around the heel and toe and along the sole, thus shaping the stocking to conform to the foot and preventing 115 distortion of the heel and toe pockets, and the formation of wrinkles in the instep and ankle portions.

3. The herein described process of knitting a seamless stocking having narrowed and widened heel and toe pockets, which consists in knitting the leg of the stocking by circular knitting with a fine thread and a tight stitch, then knitting the heel pocket by reciprocating knitting and narrowing 120 and widening, then knitting the upper part of the foot with the fine thread and a tight stitch and knitting the sole portion with said fine thread with the addition of a splicing 125 thread and lengthening the stitches of the 130

spliced sole portion to make the sole portion sufficiently longer than the corresponding part of the top of the foot, and then knitting the toe pocket by reciprocating knitting and narrowing and widening whereby the strain on the fabric, in use, will be greater over the top of the foot than around the heel and toe and along the sole, thus shaping the stocking to the foot and preventing distortion of the heel and toe and the formation of wrinkles in the instep and ankle portion.

4. The herein described process of knitting a seamless stocking, which consists in knitting the leg portion by circular knitting with a fine thread and with a tight stitch, knitting the heel pocket with a heavier thread by reciprocating knitting and narrowing and widening and with a longer stitch than the leg portion, knitting the foot portion by circular knitting, knitting the top of the foot of the light thread and with the tight stitch and simultaneously knitting the sole portion of the light thread and a reinforcing thread, and with a sufficiently longer stitch than that of the top of the foot to make the sole portion longer than the corresponding portion of the top of the foot and knitting the toe pocket of heavier thread by reciprocating knitting and narrowing and widening and with a longer stitch than the leg portion and top of the foot, whereby the strain on the fabric in use will be greater on top of the foot than around the heel and toe and along the sole thus shaping the stocking to the foot and preventing distortion of the toe and heel, and the formation of wrinkles in the instep and the ankle portion.

5. The herein described process of knitting a seamless stocking, which consists in knitting the leg portion by circular knitting with a fine thread and with a tight stitch, knitting the heel pocket with a heavy thread by reciprocating knitting and narrowing and widening and lengthening the stitch beyond that of the leg portion, knitting the top of the foot with the light thread and tight stitch and knitting the sole portion as a heavier fabric, and lengthening the stitches sufficiently to make the sole portion longer than the corresponding top portion of the foot, and knitting the toe pocket of heavier thread by reciprocating knitting and narrowing and widening and lengthening the stitches, the thread in the heel and toe being thicker than that used in the sole portion, and the stitches in the heel and toe being of greater length than those in the sole portion, whereby the strain on the fabric, in use, will be greater over the top of the foot than around the toe and heel and along the sole thus shaping the stocking to the foot and preventing distortion of the heel and toe and the formation of wrinkles in the instep and ankle portion.

6. The herein described process of knitting a seamless stocking, which consists in knitting the leg portion by circular knitting down to a point above the upper edge of the heel pocket with a light thread, and with tight stitches, then knitting the rear portion of the leg above the heel as a heavier fabric and lengthening the stitches throughout the heavier portion so formed while continuing to knit with the light thread and tight stitch in the corresponding courses of the front of the leg, then knitting the heel pocket with a heavier thread by reciprocating knitting and narrowing and widening and lengthening the stitches of the heel to a greater extent than in the said heavier portion above the heel, then knitting the top portion of the foot with the light thread, and tight stitch and knitting the sole portion as a heavier fabric than the top of the foot and lengthening the stitches of the sole portion sufficiently to make the length of said sole portion greater than the corresponding portion of the top of the foot, then knitting the toe pocket of a heavier thread than the sole portion by reciprocating knitting and narrowing and widening and lengthening the stitches of the toe, to a greater extent than those of the sole portion and the heavier portion above the heel, whereby the strain on the fabric, in use, will be greater than around the heel and toe and along the sole, thus shaping the stocking to the foot and preventing distortion of the high spliced portion and heel and toe pockets and the formation of wrinkles in the instep and ankle portion.

7. A seamless stocking provided with narrowed and widened heel and toe pockets having the sole portion of the foot of greater length than the corresponding top portion of the foot whereby the strain on the fabric in use is greater over the top of the foot than around the heel and toe and along the sole, thus shaping the stocking to the foot and preventing distortion of and undue wear on the heel and toe, and the formation of wrinkles in the instep and ankle portion.

8. A seamless stocking provided with narrowed and widened heel and toe pockets, having the leg portion and top of the foot portion formed of thin fabric, the sole portion being of heavier fabric and of greater length than the corresponding portion of the top of the foot, whereby the strain on the fabric in use is greater over the top of the foot, than along the sole, thus shaping the stocking to the foot and preventing distortion of the toe and heel pockets and the formation of wrinkles in the instep and ankle portion.

9. A seamless stocking provided with narrowed and widened heel and toe pockets, having the main portion of the leg and top of the foot formed of thin fabric, a heavier

- portion at the back of the leg above the heel, and of greater length than corresponding courses of the front part of the leg, and a sole portion of heavier fabric than the leg and top portion of the foot, and of greater length than the corresponding courses of the top of the foot, whereby the strain on the fabric in use, is greater over the top of the foot and front of the leg, than around the heel and toe and along the sole, thus shaping the stocking to the foot, relieving the heel and toe pockets of strain and undue wear and avoiding wrinkles in the instep and ankle portion.
- 15 10. A seamless stocking provided with narrowed and widened heel and toe pockets having the leg and top of the foot formed of light fabric, the sole portion formed of heavier fabric, the stitches of the sole fabric being of greater length than in the leg portion, to give the sole portion greater length
- than the corresponding courses of the top portion of the foot, the heel and toe being formed of heavier fabric than the sole portion, and having the stitches therein of greater length than those of the sole portion, whereby the strain on the fabric when in use is greater over the top of the foot and front of leg, than it is around the heel and toe and along the sole, thus shaping the stocking to the foot and preventing distortion of the heel and toe pockets and the formation of wrinkles in the instep and ankle portion.
